Inventor:

Harold Olsen

UNITED STATES PATENT OFFICE.

HAROLD OLSEN, OF NEW YORK, N. Y., ASSIGNOR TO PHILIP BECKER AND GEORGE BECKER, OF NEW YORK, N. Y.; SAID PHILIP BECKER EXECUTOR OF SAID GEORGE BECKER, DECEASED.

ETCHING-MACHINE.

1,383,010.

Specification of Letters Patent. Patented June 28, 1921.

Application filed May 29, 1916, Serial No. 100,574. Renewed October 6, 1920. Serial No. 415,218.

To all whom it may concern:

Be it known that I, HAROLD OLSEN, a subject of the King of Norway, residing in New York city, county of New York, State of New York, have invented certain new and useful Improvements in Etching-Machines, of which the following is a full, clear, and exact specification.

This invention relates to etching apparatus and the object of the invention is to provide an improved machine which will project the etching fluid in a finely divided state against the surface of the plate to be etched.

It has been found that when the etching fluid is thrown perpendicularly against the surface of the plate, the tendency to "undercut" is minimized. To so project the liquid machines have been devised which direct the acid onto the plate through numerous small nozzles, or by a rotary paddle wheel. The former, or "acid blast" machines, are intricate, expensive and difficult to maintain in operation. The rotary paddle wheel type of etching machine does not produce a finely divided spray and is limited to low and practically invariable velocity. The blades of the paddle wheel scoop up the liquid and throw it in masses against the plate and successive blades cannot operate effectively unless the fluid surface has time between them to replace the liquid scooped out by each preceding blade. Due to the impact of the rotary sprayer blades with the liquid the operation of these paddle wheel machines is often disturbed by wasteful and troublesome vibrations.

It is the object of this invention to overcome these defects and provide a simple, smooth-running, inexpensive machine which will break up the etching liquid into a fine spray and project it onto the plate with a velocity variable within wide limits. With this object in view a rotary member is provided generally circular in section and in contact with the etching liquid, a thin sheet of which adheres to the surface of the rotary member at the area of contact. At a subsequent point in the rotation of the sprayer the thin sheet of liquid is thrown off from the surface by centrifugal force, and the opposing forces due to adhesion and velocity act in such manner that the liquid is disintegrated into a fine spray and pro-

jected against the surface of the plate to be etched. The speed of rotation of the runner and the velocity of the spray are readily variable within wide limits, higher speeds producing finer spray. The circular runner of this invention rotates in practically constant contact with the liquid, is free from the splashing and vibration usual with the paddle wheel type of sprayer and the resulting smoothness of operation is attended with great gain in efficiency.

In the accompanying drawings illustrating the invention:

Figure 1 is a perspective view of an etching machine embodying the invention, one side of the tank being broken away to show the interior.

Fig. 2 is a vertical section of the machine shown in Fig. 1.

Fig. 3 is a vertical sectional view of another form of etching machine embodying the invention.

Fig. 4 is a partial elevation of a modified form of runner.

Figs. 5 and 6 are sectional views illustrating modified runner surfaces.

In the embodiment illustrated in Figs. 1 and 2, 1 is the etching liquid contained in closed tank, 2, having stand, 3, for supporting the plate, 4, to be etched at one end of the tank. At the other end of the tank the rotary runner, 5, is on shaft 6 turning in bearings 7 in the sides of the tank.

The runner 5 is of general cylindrical form and comprises a series of peripheral ridges, 10, with grooves, 11, between them having rounded convex bottoms. The axis of the runner is so placed that the grooved surface dips into the surface of the liquid. As the runner rotates the liquid adheres to its surface and is carried up with it. The irregular grooved character of the surface increases the area in contact and gives a better hold on the liquid.

The film of liquid drawn up does not attain immediately to the full velocity of the runner surface. Where it leaves the body of the liquid there is considerable slip between the runner and the film but the velocity of the film is gradually accelerated till it attains such a speed that the centrifugal forces acting are greater than the force of adhesion. The particles of the film then fly off the periphery of the runner as a fine

spray. Due to the irregular surface contour of the runner all parts of the film do not reach the critical parting velocity at once. The liquid within the grooves is later to leave for it is more strongly held and its velocity is lower. It runs up the sides of the grooves gradually and consequently the spraying action does not take place at a single line across the periphery of the runner but throughout a considerable area. This spraying area is variable in extent and position by variations in the diameter and speed of the runner and the size and character of the grooves with relation to the character of the liquid being sprayed and the height of its surface. These factors are chosen to so locate this area that the spray is directed evenly over the surface of the plate 4. The velocity of the runner may be varied within wide limits, as by shifting the driving belt from one to the other of pulleys 13, while only slightly affecting the rate of etching, and the higher speeds produce finer and swifter sprays adapted for fine line work.

To utilize the spray not directed against the plate, deflector guide 8 having a depending lip 8' is mounted to overhang the runner 5 and is made vertically adjustable. This guide is particularly important at high speeds and intercepts the upwardly directed spray and drips or deflects it back onto the runner so that it may form useful spray projected against the plate. The surfaces of fillets 15 and 16 serve to avoid the sharp corners. In the embodiment shown in Fig. 1 the runner, seven inches in diameter, is designed to rotate at speeds of over fifteen hundred feet per minute, these figures being, of course, merely illustrative.

In Fig. 3 a tank, 19, is shown in sectional view provided with two oppositely rotating runners, 17, directing their spray upwardly between the guides, 18. At the top of the tank is provided means for automatically clamping and sustaining a plate face downward in the line of the spray. The hinged cover, 20, carries the clamping block, 21, fixed on its under surface. A sliding clamping block, 22, is also provided, held on the cover by pivot stud, 23, sliding in slot 24. Pivoted to stud 23 is the rod, 25, sliding in the tubular rod, 26, pivoted to an offset of the tank, 19. A pin, 27, on rod 25 slides in a slot in rod 26 and limits the inward movement of rod 25. A compression spring, 28, presses against the pin 27 to draw the rod 25 into the rod 26.

The parts are so proportioned and the pivots so arranged that when the cover 20 is open and inclined backward, as shown in dotted lines, pin 27 is at the bottom of the slot in rod 26 and stud 23 is at the top of slot 24. In this position a plate, 30, to be etched is placed between the proper steps

of the clamping blocks 21, 22. As the cover, 20, is closed the offset pivot of rod 26 causes the clamping block 22 to be moved downwardly to clamp plate 30. The relative distances between the steps of the clamping blocks are so arranged that the plate is always clamped before the cover 20 passes beyond the vertical. Further closing movement of the cover then acts simply to compress the spring 28. In this manner the plate to be etched is automatically clamped without time wasting adjustments of holding jaws.

In Fig. 4 is shown a modified form of runner in which the ridges, 35, and grooves, 36, are in the form of a helix. By this arrangement continuous horizontal displacement of the spraying surfaces is attained with a more uniform distribution of the spray.

In Fig. 5 is shown in section a form of runner contour in which the disks or ridges, 37, are separated by relatively narrow grooves, 38. Such a form of runner is adapted to give a large area of spray in comparison to its diameter, for the liquid leaves the deep grooves, 38, only gradually.

Fig. 6 shows a section of a runner contour in which the ridges 39 and 40 form undercut grooves between them. To break the continuity of ridges 39 grooves 41 are formed in them.

It is evident that the strength and the relative surface height of the etching fluid may be varied to control the etching effect. The runner periphery instead of being perfectly cylindrical may be tapered at the ends or otherwise altered in contour to properly locate the main body of the spray. It is also apparent that the etching liquid may be poured or sprayed onto the runner surface and that the form of sprayer herein disclosed may be used to project other liquids. It is to be understood that the invention is not confined to the particular embodiments described but covers such modifications thereof as fall within the scope of the appended claims.

Having thus described my invention what I claim to be new and desire to secure by Letters Patent is:—

1. In an etching machine the combination with a tank for the etching liquid having a support for the plate to be etched of a circular member having continuous grooves extending around its periphery adapted to rotate in constant contact with the etching liquid and project said liquid against said plate.

2. In an etching machine a rotary member having spaced grooves on its periphery extending substantially in the direction of rotation and adapted to rotate in contact with the etching fluid to disintegrate said fluid into a spray.

3. In an etching machine a rotary cylinder having a helical groove on its periphery adapted to rotate in constant contact with the etching liquid and acting to disintegrate 5 said fluid into a spray.
4. In an etching machine the combination with a tank for the liquid and a support for the plate, of a rotary projector comprising a circular member substantially cylindrical 10 in form and having spaced grooves extending around its periphery in the general direction of rotation of the member, and means for rotating said member at different speeds.
- 15 5. A centrifugal liquid spraying means, comprising a circular member adapted to rotate in contact with the liquid and having peripheral ridges separated by shallow grooves with bottoms normally contacting 20 with the surface of the etching liquid.
6. In an etching machine a tank containing spraying means for projecting the liquid upwardly, a pivoted tank cover carrying fixed and sliding clamping blocks, and an

extensible link connecting between said sliding block and said tank acting to automatically move said block on movement of said cover.

7. A liquid spraying means comprising a rotary member having a series of closely spaced ridges extending around its periphery and adapted to rotate in contact with the etching liquid and project said fluid from said periphery by centrifugal force, and means for rotating said member. 35

8. In an etching machine the combination with a container for the etching fluid and a holder for the plate to be etched, of a rotary sprayer having generally circular sections of variable diameter at successive 40 points along the axis of rotation, the peripheries of said sections being in contact with the etching fluid and acting to project said fluid against said plate by centrifugal force.

In testimony whereof I have hereunto set 45 my hand this 29 day of April, 1916.

HAROLD OLSEN.
